UNITED STATES PATENT OFFICE.

WILLIAM A. LORENZ, OF WEST HARTFORD, CONNECTICUT; PHOEBE BUNKER LORENZ
EXECUTRIX OF SAID WILLIAM A. LORENZ, DECEASED.

MACHINE FOR MAKING ELASTIC PAPER.

Application filed April 9, 1927. Serial No. 182,304.

The aim of the present invention is to provide an improved method of and apparatus for corrugating and crinkling paper at a high rate of production and without injury 5 to the paper.

More particularly, an aim of the invention is to provide certain improvements in a machine of the type shown in my Patent No. 1,548,788, dated August 4th, 1925.

Other objects will be in part obvious and in part pointed out more in detail hereinafter.

The invention accordingly consists in the features of construction, combination of elements and arrangement of parts which will be exemplified in the construction herein-after set forth, and the scope of the application of which will be indicated in the appended claims.

In the accompanying drawings, wherein I have shown, for illustrative purposes, one embodiment which the present invention may take:

Fig. 1 is a vertical longitudinal view 25 through my improved machine;

Fig. 2 is a top plan view;

Fig. 3 is an enlarged view showing in detail the manner in which the paper is crinkled as it passes from the cylinder 10 to the cylinder 11;

Fig. 4 is a sectional view taken substantially on line 4-4 of Fig. 1; and

Fig. 5 is an inside view of the forward end of the plate 21.

In accordance with the present invention, I provide a series of cylinders so arranged that the paper is delivered from one to the other, each successive cylinder running at a lesser speed than the preceding one so as to effect a retardation in the speed of the paper, accordingly resulting in crêping or crinkling the same on transverse lines. These cylinders are preferably circumferentially corrugated and certain of the cylinders are roughened or provided with teeth to facilitate the crinkling action as the paper is delivered thereto. Also, the cylinders are provided with stationary plates for holding the paper on the cylinders during the crinkling operations, these plates being provided with corrugations which match with the corrugations of the respective cylinders with which they are associated. In the accompanying drawings, the machine is shown more or less diagrammatically.

Referring to the drawings in detail, I

have shown three cylinders 10, 11 and 12, the first cylinder 10 being provided with circumferential corrugations 13. The second cylinder 11 is also circumferentially corrugated, and these corrugations match with the corrugations 13 of the cylinder 10. The corrugations of the cylinder 11 are transversely grooved so as to form clearances 14 and teeth 15. The teeth 15 by preference notch with and extend into the grooves between the ribs of the cylinder 10, but they do not scrape or touch the cylinder 10 so that tearing or injury to the paper is avoided. The rear face of each tooth 15 is preferably radial while the advancing face is preferably oblique, as shown most clearly in Figs. 1 and 3.

The cylinder 12 which receives the paper from the cylinder 11 is similar to the cylinder 11 but rotates in the opposite direction. The cylinder 12 has rings of teeth 16 which match with the grooves in the cylinder 11 in the same manner as do the teeth 15 match with the grooves of the cylinder 10.

Associated with the respective cylinders 10, 11 and 12 are curved plates 20, 21 and 22 which are generally similar in construction. The plate 20 is curved concentrically to the cylinder 10 and is provided on its concave face with ribs 23 which match with the annular grooves in the periphery of the cylinder 10. Similarly, the plate 21 has ribs 24 which match with the grooves of the cylinder 11, and the plate 22 has ribs 25 matching with the grooves of the cylinder 12.

The plates are preferably adjustable so as to vary the distance between them and the respective cylinders, it being desired that while the plates are so located as to hold the paper on the cylinders, they do not so closely fit the cylinders as to interfere with the paper being carried thereby. In the present illustrative disclosure, the plate 20 is pivoted at one end as at 30 and its other end is adjustable. The manner in which this plate and the other plates are adjustable may be varied as desired, but by way of example I have shown the plate 20 as having an arcuate slot 31 which receives a screw 32 carried by the frame of the machine. The plate 21 may be vertically adjusted through the gears 33, one of these gears being located on a threaded stud 34 depending from the plate 21. The plate 21 may be clamped in adjusted position by the screws 35. The plate 22 is pivoted as at 36 and is clamped in any desired position.

of adjustment by the screw 37. It will be seen that the forward end of the plate 21 is corrugated so as to provide fingers or teeth 38 which extend into the grooves in the cylinder 10 so as to strip the paper from that cylinder as it is delivered to the cylinder 11. The plates 21, 22 and 23 may be of any suitable length and their concave surfaces are smooth.

The cylinders may be supported in any suitable frame, but by way of illustration I have shown this frame as comprising a pair of side members 40 secured together by tie rods 41. The cylinders are geared together so that the successive cylinders rotate at relatively slower speeds. In the present illustrative disclosure, the shaft 45 of the cylinder 10 is provided with a gear 46 which meshes with a larger gear 47 fixed to the shaft 48 of the cylinder 11. Fixed on this shaft is a gear 49 which meshes with a larger gear 50 on the shaft 51 of the cylinder 12. This train of gears may be driven from a gear 52 fixed on a main shaft 53 and meshing with the gear 46. Suitable change gears may be employed if desired.

Cooperating with the cylinder 10 is a companion spring pressed roller 55 which is circumferentially corrugated as indicated in Fig. 2 so as to mesh with the corrugations of the cylinder 10 whereby the web, as it passes between these members, is longitudinally corrugated. The roller 55 may be rubber covered. The paper may be delivered to the roller 55 from a roll of paper 56. It will be found of advantage to moisten the web of paper and this may be done in any suitable manner as, for example, by spraying the water onto the paper from suitable pipes 60. The number of pipes 60 may be as desired and some of those shown may be omitted. The roller 55 may be driven at the same peripheral speed as the cylinder 10 as, for example, through the gears 61 and 62.

The operation of the machine is briefly as follows: As the paper passes between the cylinder 10 and the roller 55, it is wetted and is caused to conform to the circumference of the cylinder 10, resulting in the paper being corrugated. The cylinder 10 carries the corrugated paper into the throat between the cylinder 10 and the cylinder 11 where it is stripped off from the cylinder 10 and cross crinkled by the teeth on the cylinder 11. The cylinder 11 carries the paper into the throat between itself and the cylinder 12 and delivers the paper to the cylinder 12. As the paper is transferred from the cylinder 11 to the cylinder 12, it is further crinkled owing to the slower movement of the cylinder 12. The cylinder 12 delivers the crinkled paper to a suitable belt 63. Obviously, the machine may be employed to operate on fabric webs other than of paper.

I claim as my invention:

65 1. In a machine of the character described,

a pair of cooperating cylinders one delivering to the other, each of said cylinders being provided with circumferential corrugations and the receiving cylinder being revolved at a slower speed than the delivering one, and plates curved about said cylinders and having corrugations matching with those of the cylinders.

2. In a machine of the character described, a pair of cooperating cylinders one delivering to the other, each of said cylinders being provided with circumferential corrugations and the receiving cylinder being revolved at a slower speed than the delivering one, and plates curved about said cylinders and having corrugations matching with the corrugations of said cylinders, the end of that plate about the delivering cylinder extending into the throat between said cylinders and the forward end of the plate about the receiving cylinder having fingers extending into the grooves of the delivering cylinder.

3. In a machine of the character described, a pair of cooperating cylinders one delivering to the other, each of said cylinders being provided with circumferential corrugations and the receiving cylinder being revolved at a slower speed than the delivering one, plates curved about said cylinders and having corrugations matching with those of the cylinders, and means for adjusting said plates relative to the respective cylinders.

4. In a machine of the character described, a pair of cooperating cylinders one delivering to the other, the receiving cylinder having a roughened surface and being driven at a slower peripheral speed than the delivering cylinder whereby the paper is crinkled as it is transferred from one cylinder to the other, and plates curved about said cylinders for holding the paper thereagainst.

5. In a machine of the character described, a pair of cooperating cylinders one delivering to the other, means for driving the receiving cylinder at a slower speed than the delivering one whereby the paper is crinkled as it is transferred from one cylinder to another, and means for delivering the paper to the receiving cylinder at a greater speed than the peripheral speed of said cylinder whereby the paper is partially crinkled as it is delivered to the receiving cylinder.

6. In a machine of the character described, a succession of at least three cylinders arranged to deliver a paper web one from the other, each of said cylinders having circumferential corrugations, the corrugations of each succeeding cylinder matching with the grooves of the preceding one, and means for driving each succeeding cylinder at a slower speed than the preceding one whereby the paper is transversely crinkled upon each transfer from one cylinder to another.

7. In a machine of the character described, a succession of at least three cylinders ar-

- ranged to deliver a paper web one from the other, each of said cylinders having circumferential corrugations, the corrugations of each succeeding cylinder matching with the 5 grooves of the preceding one, means for driving each succeeding cylinder at a slower speed than the preceding one whereby the paper is transversely crinkled upon each transfer from one cylinder to another, and 10 curved plates about each of said cylinders and having corrugations matching with the grooves thereof.
8. In a machine of the character described, a pair of cylinders placed close together with- 15 out contact and cooperative to form a throat, each of said cylinders on its periphery having teeth with clearances in front of the same, the receiving cylinder being driven at a slower speed than the delivering one, and means for 20 delivering a paper web to the delivering cylinder at a greater speed than the peripheral speed of said cylinder whereby the paper is crinkled as it is delivered thereto.
9. In a machine of the character described, 25 a pair of cylinders placed close together without contact and cooperative to form a throat, each of said cylinders having on its periphery teeth with clearances in front of the same, the receiving cylinder being driven at a slow- 30 er speed than the delivering one, means for delivering a paper web to the delivering cylinder at a greater speed than the peripheral speed of said cylinder whereby the paper is crinkled as it is delivered thereto, and plates 35 curved about each of said cylinders for holding the paper thereagainst.
10. In a machine of the character described, a succession of at least three cylinders ar- 40 ranged to deliver a paper web one from the other means for driving each successive cylinder at a lesser speed than the preceding one, the second and third cylinders being provided with teeth to effect crinkling of the paper as it is delivered thereto.
11. In a machine of the character described, 45 a succession of cylinders arranged to deliver a web one from the other, the first of said cylinders having circumferential corrugations and the second and third of said cylinders having circumferential rings of teeth, the 50 rings of teeth of the second cylinder matching with the grooves of the first cylinder and the rings of teeth of the third cylinder matching with the grooves of the second cylinder, and means for driving each successive cylinder at 55 a lesser speed than the preceding one.
12. In a machine of the character described, 60 a succession of at least three cylinders ar- ranged to deliver a web one from the other, the first of said cylinders having circumfer- 65 ential corrugations and the second and third of said cylinders having circumferential rings of teeth, the rings of teeth of the second cylinder matching with the grooves of the first cylinder and the rings of teeth of the third cylinder 70 matching with the grooves of the second cylinder, means for driving each successive cylinder at a lesser speed than the preceding one, and adjustable plates curved about each of said cylinders and having ribs matching with the grooves thereof.

WILLIAM A. LORENZ.
